United States Patent Office

Des. 187,287
Patented Feb. 23, 1960

187,287

CLOCK

Gordon Florian, Bridgeport, Conn., assignor to Sunbeam Corporation, Chicago, Ill., a corporation of Illinois

Application June 20, 1958, Serial No. 51,457

Term of patent 14 years

(Cl. D42—7)

Fig. 1 is a front perspective view of a clock embodying my new design;

Fig. 2 is a top view of the clock shown in Fig. 1; and

Fig. 3 is a side elevational view of the clock shown in Fig. 1.

The back of the clock is conventional in appearance. I claim:

The ornamental design for a clock, as shown and described.
